UNITED STATES PATENT OFFICE

ADIEL V. DODGE, OF SOUTH BEND, INDIANA, ASSIGNOR TO BENDIX BRAKE COMPANY,
OF CHICAGO, ILLINOIS, A CORPORATION OF ILLINOIS

BRAKE

Application filed February 4, 1926. Serial No. 35,945.

This invention relates to brakes, and is illustrated as embodied in an internal expanding automobile brake. An object of the invention is to improve the efficiency of a brake 5 of the type in which one shoe forces another against the drum. Preferably the first shoe is anchored at one end,—well within the curve of the shoes in the brake illustrated,—by being pivotally connected to the other shoe 10 near its anchored end. It is highly desirable that this pivotal connection should be between the ends of the other shoe, so that thus each of the shoes is anchored between the ends of the other. In the arrangement shown 15 in the drawings, there is a third shoe arranged to apply the anchored shoe.

Another feature of the invention relates to the use of a spring acting on one of two connected shoes in such a manner as to hold the 20 other one of the shoes away from the drum, preferably in an idle position determined by a novel stop, until the spring is overcome by movement of the first shoe with the drum. This insures successive action of the shoes, 25 giving smooth and gradual application of the brake.

The above and other objects and features of the invention, including a novel shoe construction embodying spaced flanges between 30 the sides of the shoe and straddling part of an adjacent shoe, and other novel combinations of parts and desirable particular constructions, will be apparent from the following description of one illustrative embodiment shown in the accompanying drawing, 35 in which:

Fig. 1 is a vertical section through the brake, just inside the head of the drum, and showing the shoes in side elevation; 40 Fig. 2 is a section through the central shoe, on the line 2—2 of Fig. 1;

Fig. 3 is a section through one end shoe, on the line 3—3 of Fig. 1; and

Fig. 4 is a section on the line 4—4 of Fig. 45 1, showing the anchoring of the shoes.

The brake selected for illustration includes a drum 10, the open side of which is closed by a backing plate 12.

Within drum 10 is arranged a shoe 14, piv- 50 oted at its lower end, so that it is most effec-

tive when the drum is turning clockwise, which would be when the vehicle is moving backward. The pivoted end of this shoe curves inwardly of the drum, so that the pivot 16, which takes the torque from the shoe, thus 55 having the function of an anchor, is a considerable distance radially inward from the braking flange of drum 10, well within the curve of the brake shoes. This gives a considerable wedging effect due to the drum friction, when the drum is turning clockwise, so that the shoe so mounted has a very powerful retarding effect. Such powerful action in a single shoe would not ordinarily be desirable in a shoe retarding forward movement 60 of the vehicle, as at the high speeds of such forward movement it would give too harsh a retarding effect. At the relatively low speeds of rearward movement, however, this mounting is permissible, and gives a greatly 65 increased braking action in reverse.

Shoe 14 has a pair of oppositely-extending flanges 18 entirely around the edge of its central stiffening flange, parts of which form the cylindrically-curved friction face 20, and is thus generally T-shaped in cross-section, 70 as appears in Fig. 3.

Adjacent the lower end of shoe 14 is a central shoe 22, having a pair of spaced-apart stiffening flanges 24 spaced inwardly between 75 its edges, to straddle part of the end of shoe 14. Flanges 24 are spaced apart just enough to clear flanges 18, so that they position the shoes laterally with respect to each other. Shoe 22 is pivoted on an anchor 26 passing 80 through a relatively large opening in the straddled part of shoe 14 (Fig. 4). It is to be noted that the anchor of shoe 22 is between the ends of shoe 14 and that the pivot or anchor of shoe 14 is between the ends of shoe 22, 85 thus securing the greatest possible use of the drum surface, the friction parts of the two shoes coming immediately adjacent each other. The torque-taking means 16 of shoe 14 is in the form of a pivot connecting shoe 14 to flanges 24 of shoe 22, the anchor or pivot being shown held in place by an enlarged head slidably engaging plate 12.

At the unanchored end of shoe 22 is arranged a third shoe 28 having edge flanges 190

30 positioned by flanges 24, and connected to the end of shoe 22 by a pivot 32, which pivot serves as the anchor for shoe 28.

Shoes 14 and 28 are forced apart against the resistance of a return spring 34, to apply the brake, by means such as a double cam 36. An auxiliary spring 38 insures that shoe 28 will first engage the drum, and will then turn with the drum to overcome spring 38 and force shoe 22 against the drum. Spring 38 is connected at one end to plate 12 and at the other end to shoe 28 near its pivoted end, and thus acts through pivot 32 to hold shoe 22 away from the drum with one flange 24 against an adjustable eccentric stop 40 carried by the backing plate while shoe 28 is being swung against the drum by cam 36 or the like. This insures successive operation of the shoes, giving a smooth and gradual operation of the brake. The arrangement of this spring was disclosed in my prior application No. 23,763, filed April 17, 1925, and claims to this feature are to be regarded as divided from that application. At the same time the movement of shoe 14 urges the pivot or anchor 16 toward the drum.

When used in an automobile, Fig. 1 would be a vertical section through one left brake, just inside the wheel and looking toward the car, with the front of the car at the left, thus bringing pivots 16 and 26 at the rear of the brake.

While one illustrative embodiment has been described in detail, it is not my intention to limit the scope of the invention to that particular embodiment, or otherwise than by the terms of the appended claims.

I claim:

1. A brake comprising a pair of arcuate friction devices, in combination with torque-taking means for one of said devices a substantial distance radially within the curve of said devices, and torque-taking means for the adjacent end of the other device between the ends of the first device, one of said means being a pivot connecting the two devices.

2. A brake comprising a pair of arcuate friction devices, one including a single shoe and the other including connected shoes, in combination with torque-taking means for said single shoe a substantial distance radially within the curve of said devices, and torque-taking means for the adjacent end of one of the connected shoes between the ends of the single shoe, one of said means being a connection between two of the shoes.

3. A brake comprising, in combination, a pair of shoes, the first having a pair of flanges spaced apart from each other and both spaced inwardly from the side edges of the shoe and the other having a flange extending between and straddled by the pair of flanges, together with torque-taking means pivotally connecting the shoes and engaged by the end of said straddled flange, and torque-taking means

engaged by the pair of flanges between the ends of said other shoe.

4. A brake comprising, in combination, a pair of curved shoes, the first having a pair of flanges spaced apart from each other and the other having a flange extending between and straddled by the pair of flanges and thence offset well within the curve of the shoes and there pivoted to said flanges, and torque-taking means engaged by the pair of flanges between the ends of said other shoe.

5. A brake comprising, in combination, a pair of shoes, the first having a pair of flanges spaced apart from each other and both spaced inwardly from the side edges of the shoe and the other having a flange extending between and straddled by the pair of flanges, together with torque-taking means engaged by the ends of said pair of flanges, and means pivotally connecting the pair of flanges to the straddled flange between them.

6. A brake comprising, in combination, a pair of shoes, the first having throughout its length a pair of flanges spaced apart from each other and both spaced inwardly from the side edges of the shoe and the other having a flange extending between and straddled by the pair of flanges, together with torque-taking means engaged by the end of said straddled flange, and torque-taking means engaged by the ends of the pair of flanges, and a third shoe pivotally connected to and arranged to operate one of said pair of shoes.

7. A brake comprising, in combination, a pair of shoes, the first having a pair of spaced flanges spaced inwardly from the side edges of the shoe, and the other having a flange between and straddled by the spaced flanges, together with means connecting the shoes and taking the torque of each shoe between the ends of the other shoe, said means acting on the ends of the shoes at which the flange is straddled by the pair of flanges.

8. A brake comprising, in combination, a pair of shoes, the first having a pair of spaced flanges spaced inwardly from the side edges of the shoe, and the other having a flange between and straddled by the spaced flanges, together with means for pivoting the pair of flanges to the straddled part of said flange, and an anchor for taking the torque of both shoes by engagement with one of the shoes.

9. A brake comprising, in combination, a drum, a pair of shoes, one of which is anchored at one end, a pivot directly connecting the other end of the anchored shoe to the adjacent end of the unanchored shoe, a spring connected to the unanchored shoe and acting through the pivot to hold the anchored shoe away from the drum until overcome by movement of the unanchored shoe angularly with the drum, a third shoe, and a second spring tensioned between the unanchored shoe and the third shoe.

10. A brake comprising, in combination, a

- drum, a pair of shoes, one of which is anchored at one end, a pivot directly connecting the other end of the anchored shoe to the adjacent end of the unanchored shoe, a 5 spring connected to the unanchored shoe and acting through the pivot to hold the anchored shoe away from the drum until overcome by movement of the unanchored shoe angularly with the drum, a third shoe pivoted at the 10 end adjacent the anchored end of the first anchored shoe, and means for forcing the third shoe and the unanchored shoe in opposite directions against the drum.
11. A brake comprising, in combination, a 15 drum, a pair of shoes engageable with the drum, a connection between the shoes, and a spring connected to one of the shoes and acting through the connection and forming the sole means urging the other of the shoes 20 away from the drum.
12. A brake comprising, in combination, a drum, a pair of shoes engageable with the drum, a connection between the shoes, an anchor for one of the shoes, and a spring connected to the unanchored shoe and acting 25 through the connection and forming the sole means urging the anchored shoe away from the drum.
13. Brake mechanism for a vehicle having 30 a road wheel provided with a brake drum comprising, in combination therewith, at least three articulated arcuate brake shoes within the drum, two of which shoes are adapted to wrap with the drum to retard its 35 rotation in the forward travel of the vehicle and the third shoe is adapted to retard its rotation in the opposite direction, said third shoe provided with torque taking means located radially substantially within 40 the curve of the shoes.
14. Brake mechanism for a vehicle having 45 a road wheel provided with a brake drum comprising, in combination, a pair of retarding devices located within the drum to be urged thereagainst, one retarding device adapted to wrap with the drum in one direction of rotation to retard its travel and the other retarding device adapted to wrap with the drum in the opposite direction of rotation 50 to retard its travel, said retarding devices provided with torque taking means at adjacent ends, one of which is a pivotal connection between the two devices, and one of which is positioned substantially radially nearer the 55 axis of the drum than the other.
15. Brake mechanism for a vehicle having 60 a road wheel provided with a brake drum comprising, in combination therewith, a pair of arcuate retarding devices of unequal length arranged within the drum to be urged thereagainst, the retarding device of greater length adapted to wrap with the drum in the forward direction of travel of the vehicle and the device of less length adapted to wrap 65 therewith in the opposite direction of rota-
- tion of the drum, said devices provided with torque taking means at their adjacent ends, the torque taking means of the device of less length being positioned substantially inwardly radially of the torque taking means 70 of the device of greater length, one of said torque taking means comprising a pivotal connection between the two devices.
16. A brake comprising, in combination, a 75 drum, a pair of brake shoes arranged therein with overlapping ends engaging radially and circumferentially separated torque taking members, one of which is a fixed anchor and the other a pivot connecting the two shoes, said anchor being located substantially 80 nearer the periphery of the drum than the pivot.
- In testimony whereof, I have hereunto signed my name.
- ADIEL Y. DODGE. 85
